7 Claims. (Cl. 167—65)

The present invention relates to a new composition for lowering the cholesterol level in the blood serum.

It is known that the normal cholesterol level in the human blood serum as measured by the Grigaut and Liebermann method lies between 1.70 g. and 1.80 g. per litre. Although a higher level than this is fairly common around the fiftieth year and does not seem to be always positively serious, in many cases an increase in the cholesterol level is a sign of pathological nutritive disorders and of a disturbed metabolism. Thus the cholesterol level may become abnormally high and attain 3 g. to 3.5 g. per litre and more. This might cause if not remedied, grave vascular lesions.

Notwithstanding the many researches directed at discovering an adequate remedy, present-day therapeutic armament is very inadequate for counteracting this pathological increase in the cholesterol level.

We have now discovered a really efficient composition with which it is possible to lower the cholesterol level in the blood serum. It has been found, somewhat surprisingly, that the compounds of the general formula

in which:

R represents an alkyl or aryl radical,
R₁ represents hydrogen or an alkyl radical,
R₂ represents an alkyl or alkylene radical,
m is an integer equal to 0 or 1, and
X is a group satisfying the free valence of the radical

very significantly lower the cholesterol level in the human blood serum and render the compositions of Formula I readily tolerated by the human organism, when they are administered with an inert vehicle orally in the form of tablets, through the rectum in the form of suppositories or parenterally in the form of solutions.

The invention has for object to provide a new composition for lowering the cholesterol level in the blood serum comprising a compound of Formula I mentioned above and an inert vehicle administrable in human medicine.

This inert vehicle in the case of tablets comprises the conventional mixture of starch, magnesium stearate and talc used in forming tablets. In the case of suppositories, the vehicle is cocoa butter or any other conventional excipient. In the case of solutions the vehicle is water or an appropriate solvent.

As has been mentioned above, the group X satisfying the free valence of the radical of Formula II may vary. Indeed, it is the radical (II) which constitutes the active part of the composition which is effective in lowering the cholesterol level in the blood serum independently of the nature of the group X. The latter must merely be such

2

that the compound of Formula I is well tolerated by the organism. Thus in particular the group X may be:

5 A —OH group, the compound I being a carboxylic acid; bearing in mind, however, the high acidity of this type of acid it is advantageous in this case to include in the inert vehicle a neutralizing agent such as a carbonate, a bicarbonate or magnesia.

A —OM_{en} group, M_{en} being a metal readily tolerated by the organism such as Na, Mg, Al and n being a fractional index such that the product of the latter and the valence of M_{en} is equal to 1; the compound I is thus a neutral metallic salt generally readily tolerated by the organism. In certain cases, however, it is not advisable to use certain metallic salts when the cation such as sodium is prohibited in the diet of the patient.

A —OB group, B being the cation of an organic base such as piperazine; the compound I is then a readily-tolerated aminated salt.

A NH₂ group, the compound I is then an amide. This form is particularly advantageous since the amides are not acids and permit fairly often avoiding an intolerance from a digestive point of view, are devoid of metallic ions, which are sometimes contraindicated, and are but little hygroscopic.

25 The compounds of Formula I, in which R, R₁ and R₂ vary within the indicated limits, are all more or less active for the intended purpose depending on the nature of the radicals R₁ and R₂. The preferred compounds are those in which R is an alkyl radical having 1 or 2 carbon atoms, the radical phenyl or the radical naphthyl, R₁ is hydrogen or an alkyl radical having 1 to 2 carbon atoms, R₂ is an alkyl or alkylene radical having 1 to 7 carbon atoms.

30 The elements of Formula I are generally known, a certain number of them having been described in chemical works.

The processes of preparing these compounds naturally vary with the nature of the R, R₁ or R₂ substituents. Owing to their great number it is not possible to describe all of them in detail, which is in any case unnecessary since they are all based on conventional organic chemistry processes.

35 However, by way of example, we shall give below details of a suitable process for certain particular cases.

It comprises, m being equal to 0 and when R is a phenyl, R₁ hydrogen, R₂ an alkyl or an alkylene, preparing from phenylacetone, C₆H₅—CH₂—CN, the sodium derivative C₆H₅—CHNa—CN by the action of sodium amide and condensing this body with a halogenide XR₂. There is thus obtained a derivative of the formula

40 which is hydrolyzed so as to replace the CN group by a COOH group.

45 If R₁ is also an alkyl radical it suffices before effecting the hydrolysis for replacing CN by COOH to subject the obtained compound to the same sequence of operations. In this way the second radical R₁ is introduced.

The derivatives of Formula I have had heretofore very 50 few commercial applications and in any case have never been recommended for therapeutic use in the form of a new composition comprising the derivatives of Formula I and the aforementioned inert vehicle in modifying the cholesterol level in the blood serum.

55 The new composition embodying the invention may be advantageously made up in the form of 50 cg. (500 mg.) tablets composed for example of:

70 80% compound of Formula I i.e. 40 centigrams
14% starch
4% magnesium stearate
2% talc

3 to 6 of these tablets per day may be prescribed, according to the gravity of the case. The derivatives of Formula I are practically without toxicity and no contraindication opposes the administration thereof.

There will now be given some clinical results obtained with the new composition in this particular tablet form, it being understood, as mentioned above, that other therapeutic forms may be used.

Phenylethylacetamide (compound of Formula I in which $R \approx \text{phenyl}$, $R_1 = \text{H}$, $R_2 = \text{ethyl}$, $m = 0$, $X = \text{NH}_2$) has been tested on 102 patients in daily doses of 6 tablets of the aforementioned composition.

For the purpose of a better analysis of the effect of phenylethylacetamide, the patients were divided into five groups in accordance with the blood cholesterol level. For each group the mean blood cholesterol level was ascertained before treatment and then again in the course of the second, fourth, sixth and if desired the eighth week after the start of the treatment.

In the first group (6 patients having a cholesterol level exceeding 3.50 g.), the mean cholesterol level dropped from 4.83 g. before treatment to 3.92 g. in the second week of the treatment, 2.93 g. in the fourth week and 2.87 g. in the sixth week; the drop in the cholesterol level was therefore 40% in 6 weeks.

In the second group (18 patients having a cholesterol level between 3 g. and 3.49 g.), the mean cholesterol level dropped from 3.05 g. before treatment to 2.47 g. in the second week, 2.31 g. in the fourth week and 2.23 g. in the sixth week; the drop was therefore 26% in 6 weeks.

In the third group (34 patients having a cholesterol level between 2.50 g. and 2.99 g.), the mean cholesterol level dropped from 2.60 g. before treatment to 2.14 g. in the second week, 2.01 g. in the fourth week and 1.83 g. in the sixth week; the drop was therefore 29% in 6 weeks.

In the fourth group (32 patients having a cholesterol level between 2 g. and 2.40 g.), the mean cholesterol level dropped from 2.17 g. before treatment to 1.90 g. in the second week, 1.93 g. in the fourth week and 1.82 g. in the sixth week; the drop was therefore 11% in 6 weeks.

In the fifth group (12 patients having a cholesterol level between 1.50 g. and 1.99 g., i.e. practically normal), the mean cholesterol level dropped from 1.85 g. before treatment to 1.77 g. in the second week and 1.79 g. in the fourth week; the drop was therefore 3% in 4 weeks.

As can be seen from the foregoing figures, the percentage drop is greater as the starting cholesterol level is higher. When the cholesterol level is normal, the composition has little effect.

The medicine was readily tolerated, the urinary functions always remained normal and there were no changes in the blood formula.

From the foregoing facts it is therefore possible to say that phenylethylacetamide normalizes the cholesterol level in the blood serum without seeming to lower it below the normal level.

Substantially similar results have been obtained with sodium phenylethylacetate which differs from the foregoing composition only in the modification of the group X in ONa instead of NH_2 —as well as with other metallic salts or organic base salts of phenylethylacetic acid. From this it is clear that the active part of the composition is the radical of Formula II, the group X having no effect on the result except that the compounds of Formula I, being dependent on the nature of X , may be rendered more or less tolerated by the organism.

The following Table I shows that in modifying the nature of the R , R_1 and R_2 substituents and the value of the index m within the indicated limits, there are obtained products which also lower the cholesterol level in a noticeable manner. The lowering of the cholesterol level given in the last column of the table is a mean percent-

age determined from a number of cases after treatment over a period of 6 weeks at the rate of 6 tablets per day of the aforementioned composition.

Table I

Reference No. of the tested composition	R	R_1	R_2	m	X	Percentage drop in cholesterol level
1	phenyl	H	methyl	0	ONa	30-40
2	do	H	propyl	0	ONa	20-25
3	do	H	butyl	0	ONa	¹ >15
4	do	H	heptyl	0	ONa	¹ >15
5	do	methyl	methyl	0	ONa	20-30
6	do	ethyl	ethyl	0	ONa	20-30
7	do	methyl	do	0	ONa	¹ >15
8	do	H	allyl	0	ONa	25-30
9	naphthyl	H	ethyl	0	ONa	>15
10	phenyl	H	do	1	ONa	25-30
11	ethyl	H	do	0	ONa	¹ >15
12	phenyl	H	methyl	0	NH_2	30-40
13	do	H	propyl	0	NH_2	20-25
14	do	H	butyl	0	NH_2	20-30
15	do	H	heptyl	0	NH_2	¹ >15
16	ethyl	H	ethyl	0	NH_2	20-35

¹ Results corresponding to first experiments, the experiments being as yet uncompleted.

As can be seen from the table, the compositions of Formula I are all more or less effective depending on the nature of the radicals R_1 and R_2 and the value of the index m .

Further, a comparison of the results obtained with the compositions 1, 2, 3, 4 and 11 with those obtained with the compositions 12, 13, 14, 15, and 16 respectively clearly shows that if the radicals R , R_1 and R_2 and the index m remain the same, the activity of the composition is practically independent of the nature of X .

This observation is confirmed when X instead of being given the values $-\text{ONa}$ and $-\text{NH}_2$ is given the values $-\text{OH}$, $-\text{OM}_\text{en}$ and $-\text{OB}$ previously indicated, provided a neutralizing agent is added to the inert vehicle when $X \approx -\text{OH}$.

Thus the invention provides an efficient composition for lowering the cholesterol level and thus contributes to therapeutic armament a new remedy.

This composition is indicated in all cases of high cholesterol level whatever the origin.

It is particularly recommended in the following disorders:

Arterial disorders:

Atheromatosis and atherosclerosis

Coronary artery disease (myocardial infarction)

Angina pectoris

Arteritis of the lower limbs

Cerebral arteritis

Aortitis

Diabetes

Familial xanthomatosis

High blood pressure

Lipoid nephrosis

Chronic nephritis

Hypothyroidism

The invention is not limited to the described modes of carrying it into effect which have been given merely by way of example.

Having now described our invention what we claim as new and desire to secure by Letters Patent is:

1. A process for lowering the cholesterol level in the blood serum which comprises administering to a patient having an abnormally high blood cholesterol level, a composition comprising a pharmacologically-acceptable compound having the formula

75 wherein R is a member of the group consisting of the

allyl radical and an alkyl radical having 1 to 7 carbon atoms, m is an integer selected from the group consisting of 0 and 1, and X is an anionic grouping selected from the group consisting of —OH, —OMe, —OB, and —NH₂, wherein Me is a pharmacologically acceptable alkali metal, and B is the cation of a pharmacologically-acceptable organic base, and an inert vehicle therefor.

2. A process for lowering the cholesterol level in the blood serum which comprises administering to a patient having an abnormally high blood cholesterol level, a composition in dosage unit form comprising a solid pharmaceutical carrier and a significant amount of a pharmacologically-acceptable compound having the formula

wherein R is a member of the group consisting of the allyl radical and an alkyl radical having 1 to 7 carbon atoms, m is an integer selected from the group consisting of 0 and 1, and X is an anionic grouping selected from the group consisting of —OH, —OMe, —OB, and —NH₂, wherein Me is a pharmacologically acceptable alkali metal, and B is the cation of a pharmacologically-acceptable organic base.

3. A process for lowering the cholesterol level in the blood serum which comprises administering to a patient having an abnormally high blood cholesterol level a composition comprising phenyl ethyl acetamide together with an inert vehicle therefor.

4. A process for lowering the cholesterol level in the blood serum which comprises administering to a patient having an abnormally high blood cholesterol level a

composition comprising sodium phenyl ethyl acetate together with an inert vehicle therefor.

5. A process for lowering the cholesterol level in the blood serum which comprises administering to a patient having an abnormally high blood cholesterol level a composition comprising sodium phenyl allyl acetate together with an inert vehicle therefor.

10 6. A process for lowering the cholesterol level in the blood serum which comprises administering to a patient having an abnormally high blood cholesterol level a composition comprising sodium phenyl heptyl acetate together with an inert vehicle therefor.

15 7. A process for lowering the cholesterol level in the blood serum which comprises administering to a patient having an abnormally high blood cholesterol level a composition comprising sodium phenyl ethyl propionate together with an inert vehicle therefor.
